DESIGN FOR A BOTTLE

Ronald H. Dallas, Southgate, Calif., assignor to Glass Containers, Inc., Los Angeles, Calif., a corporation of California

Application November 25, 1935, Serial No. 59,733

Term of patent 7 years

To all whom it may concern:

Be it known that I, Ronald H. Dallas, a citizen of the United States, residing at Southgate, in the county of Los Angeles, State of California, have invented a new, original, and ornamental Design for a Bottle, of which the following is a specification, reference being had to the accompanying drawing, forming part thereof.

Fig. 1 is a face view of the bottle showing my new design;

Fig. 2 is an edge view; and
Fig. 3 is a top plan view thereof.

The side and edge of the bottle opposite that shown in the figures are substantially identical in appearance.

I claim:

The ornamental design for a bottle as shown and described.

RONALD H. DALLAS.
